UNITED STATES PATENT OFFICE.

JOHN W. MAILLOT, OF NORTH ATTLEBOROUGH, MASSACHUSETTS, ASSIGNOR
TO THE F. M. WHITING COMPANY, OF SAME PLACE.

DESIGN FOR A HANDLE FOR SPOONS, &c.

SPECIFICATION forming part of Design No. 26,268, dated November 17, 1896.

Application filed September 15, 1896. Serial No. 605,948. Term of patent 3½ years.

To all whom it may concern.

Be it known that I, JOHN W. MAILLOT, a citizen of the United States, and a resident of North Attleborough, in the county of Bristol and State of Massachusetts, have invented and produced a new and original Design for the Handles of Forks, Spoons, and the Like, of which the following is a specification, reference being had to the accompanying drawings, showing a part thereof.

In the drawings, Figure 1 represents a front face view of a spoon-handle ornamented according to my design. Fig. 2 is a similar view of the rear face of the spoon-handle.

The design consists of the following features, arranged, respectively, upon the front and rear faces and following the outline of the handle.

At the head of the handle A, upon its front face, is located on either side a compound scroll 1, with a central projection 1^a at the point where the scrolls approach each other at the top. Below the scrolls 1 are arranged the scrolls 2 2, with shell-like centers 2^a 2^b, and below these are similar scrolls 3 3, while between the upper portions of the scrolls 3 3

is a U-shaped bead or scroll 3^a. Below the scrolls 3 3 are a series of scrolls 4 4, extending centrally to the lower end of the handle. The central portion A' of the handle is plain 30 and convexed in the usual manner.

On the rear face of the handle the semi-circular scrolls 5 5 appear, one on each side of the projection 1^a, while below the lower ends of these appear the scrolls 5^a and 5^b. 35 Below these are the scrolls 6 6, having shell-like centers 6^a, next to which scrolls are the smaller scrolls 7 7 and 7' 7', curving inwardly. Next to the scrolls 7 are other scrolls 8 8, with shell-like centers, and the ogee scrolls 9 form 40 the termination of the design upon the rear face. The central portion A' is plain and convexed similar to the front central portion.

What I claim is—

The design for a spoon or fork handle substantially as herein shown and described. 45

In testimony whereof I affix my signature in presence of two witnesses.

JOHN W. MAILLOT.
